INTEGRATING APPARATUS

Roswell W. Gilbert, Montclair, N. J., assignor to
 Weston Electrical Instrument Corporation,
 Newark, N. J., a corporation of New Jersey

Application September 29, 1951, Serial No. 248,923

3 Claims. (Cl. 235—61)

1

This invention relates to apparatus for time integrating a variable quantity with respect to time and more particularly to electrical apparatus for integrating a voltage or current which varies in magnitude with a factor such as temperature, light, etc.

Integrating apparatus of the general type contemplated by this invention is shown and described in my United States Patent Number 2,575,951, issued November 20, 1951, and entitled Integrating Apparatus. The present invention concerns an improved circuit arrangement whereby such apparatus is battery operated and the drain from the battery is limited to surges of short time duration promoting long battery life. Such improved apparatus is particularly adapted for use in outlying areas lacking a readily available alternating current source, and wherein the services of an attendant are available only at infrequent intervals. One such use is in normally-unattended agricultural and weather stations for the time integration of light radiation.

An essential element of the electrical integrating apparatus is a permanent-magnet movable-coil instrument relay of relatively high sensitivity having no mechanical restoring force and so designed and constructed that the angular velocity of the movable coil is proportional to the current or the voltage applied to the coil. An integrating relay of this type is described and claimed in my prior Patent No. 2,239,363, Integrating Apparatus, granted April 22, 1941.

An object of this invention is the provision of a battery operated integrating apparatus of improved structural and operating characteristics.

An object of this invention is the provision of a battery operated integrating apparatus in which successive contact closures of an integrating instrument develop pulse type advances of a counting mechanism through a pair of polarity-reversing relays whereby the drain imposed upon the battery occurs only for a short period of time upon contact closure of the integrating instrument.

These and other objects and advantages of the invention will become apparent from the following specification when taken with the accompanying drawing in which the single view is a schematic circuit diagram of a photoelectric integrator embodying the invention.

The light sensitive element of the integrating apparatus is a photocell 10, preferably of the barrier layer or self-generating type, that is connected to the input terminals 11. Such photocell

2

generates a current proportional to the magnitude of light striking the active surface. The photocell current is passed through a divided shunt comprising the resistors 12, 13 and is reversibly passed through the movable coil 14 of the sensitive integrating relay 15. The reverse current flow through the integrating relay 15 is accomplished by a reversing relay 16 having a movable coil 17 carrying the movable contact 18, and a pair of stationary contacts 19, 20 that are connected directly to the ends of the shunt resistors 12, 13 by the wires 21, 22, respectively. When the movable contact 18 engages the stationary contact 19 the photocell current flows through the movable coil 14 of the integrating relay 15 in one direction and such current flow is reversed upon closure of the movable contact 18 with the other stationary contact 20. Since the movable contact arm 18 of the reversing relay 16 is attached to the relay coil 17 closure of one or the other contact sets of the reversing relay is controlled by the direction of current flow through the relay movable coil. The means for reversing the current flow in the coil of the reversing relay will be described in detail hereinbelow. It may here be pointed out that the reversing relay is provided with mildly magnetic contacts so that the movable contact arm will engage one stationary contact and remain so engaged until a surge of reverse current produces a similar engagement of the opposite contact.

The sensitive integrating relay 15 is of the permanent magnet-movable coil type as described in detail in my referenced United States Patent No. 2,239,363. The instrument construction is similar to that of sensitive milliammeters or microammeters but differs therefrom in that the spring connections to the movable coil 14 impose substantially no torque load on the movable system and the coil is wound on a metal frame, or is shunted by a resistance, which damps the coil so that the angular velocity of the coil is proportional to the applied current or voltage. The movable coil 14 oscillates in a magnetic field provided by a conventional permanent magnet and each half-cycle of movement of the movable contact arm 25 from one relatively fixed contact 26 to the other contact 27 (and vice versa) corresponds to a preselected quantity of light, in foot-candle-seconds, or meter-candle-seconds, falling upon the photocell 10. Therefore, the total quantity of light, for any period of time, may be measured by counting the number of half-cycles or of cycles of oscillatory movement of the movable contact arm 25 of the integrating instrument.

An electro-magnetic counting mechanism suitable for counting the half-cycle oscillations of the integrating relay 15 comprises a motor having a permanent magnet rotor 30, a field winding 31 having a phase-shifting capacitor 32 connected in parallel thereto, and a field winding 33. When the series connected field windings of the motor are energized by a short pulse of direct current the rotor 15 advances one salient pole. The step-by-step rotation of the rotor results in the progressive operation of a mechanical totalizer 34 that is connected to the rotor by the shaft 35.

The energization of the motor field windings is controlled by a second reversing relay 40 having a movable coil 41 carrying the movable contact arm 42, and a pair of stationary contacts 43, 44. This relay 40 is similar in construction to the reversing relay 16 and is adapted to alternate contact closures in response to reverse current surges impressed upon its movable coil. The movable coils of both reversing relays 16 and 40 are connected in series whereby the respective movable contact arms simultaneously will cross over to the opposite, associated stationary contact.

Power for operation of the device is supplied by a battery 45 across which are connected the surge capacitors 46, 47 by the wires 48, 49, respectively. The capacitors are arranged in series, each having one side connected to the motor field winding 31 by the wire 50. The other motor field winding 33 is connected to the movable contact arm 42 of the reversing relay 40 by the wire 53. It will be noted that the stationary contact 43, of the reversing relay 40, is connected to one side of the battery by the lead 51, and the other stationary contact 44 is connected to the opposite side of the battery by the lead 52 joined to the lead 48. Therefore, current can only flow through the motor field windings when one or the other sets of reversing relay contacts are closed and that such current flow can only be a brief surge that exists during the charging of the surge capacitors 46, 47 since one or the other of these capacitors are interposed between the motor field winding and the battery return lead.

The operation of the device will now be described starting with the contacts of the two reversing relays 16 and 40 closed as shown in the drawing. Current from the photocell 10 flows through the lead 55, the contact arm 18 (of the relay 16), the stationary contact 19, lead 21, resistor 12 and lead 59, returning to the photocell. This develops a potential across the resistor 12 which potential is applied to the movable coil 14 (of the relay 15) through the resistor 13 and the leads 56 and 58. The arm 25 of the integrating relay, therefore, deflects toward the stationary contact 27 at a velocity proportional to the magnitude of the current, or as has been explained, proportional to the quantity of light striking the photocell surface. When the integrating relay contacts 25, 27 close, current from the battery 45 flows through the leads 48 and 57, closed contacts 25, 27 (of the integrating relay) leads 60, 61 through the movable coil 41 of the reversing relay 40, leads 62, 63 and 64, through the movable coil 17 of the reversing relay 16, leads 65 and 66, the current limiting resistor 67, and leads 68, 49, 51 back to the other side of the battery. The current limiting resistor 61 has a value such that the magnitude of the current flow is sufficient to dis-engage the movable contact arms of the reversing relays from their associated stationary contacts and cross over to

establish contacts with the opposite stationary contacts. Such cross over of the reversing relays brings the following operations into effect.

1. The current from the photocell is reversed in the movable coil of the integrating relay 15. Such current flow now follows the path defined by the lead 55, reversing relay contacts 18, 20, leads 22, 58, integrating relay coil 14, leads 57, 56, resistor 12 and lead 59.

2. The closure of the contacts 42, 44 of the reversing relay 40 completes a series circuit across the battery 45 such circuit comprising the leads 48, 52, relay contacts 42, 44, lead 53, motor field windings 33, 31, leads 50, surge capacitor 47, leads 49, 51. A surge or pulse, of current, therefore, flows through the motor field windings and the surge capacitor. This current pulse is of brief duration but sufficient to produce a rotation of the motor rotor an angular distance equal to one rotor tooth.

3. The totalizing mechanism 34 advances one unit count.

4. Since the current through the movable coil of the integrating relay 15 has reversed direction immediately upon closure of the contacts 18, 20 of the reversing relay 16, the movable arm 25 of the integrating relay immediately leaves the stationary contact 27 and moves toward the other stationary contact 26. Such opening of the contacts 25, 27 opens the circuit to the series-connected movable coils of the reversing relay. Thus, it will be apparent the device operates on current pulses effective only upon the momentary closure of the contacts of the integrating relay.

Upon completion of the half cycle of operation just described the power elements of the apparatus are in the "at rest" or de-energized position with no current being drawn from the battery. The sensitive integrating relay alone remains active, its movable coil energized by the photocell current and moving toward the stationary contact 26 at a velocity proportional to the quantity of light striking the photocell. When, finally, the integrating relay contacts 25, 26 close, current from the battery 45 flows through the leads 48, 51, closed contacts 25, 26 (of the integrating relay) leads 66, 65, the movable coil 17 (of the reversing relay 16), leads 64, 53, 62, the movable coil 41 (of the reversing relay 40), lead 60, the current-limiting resistor 10, and leads 49 and 51 back to the other side of the battery. It will be noted the direction of the current flow through the movable coils of the reversing relays is now reverse to that which prevailed during the previous half-cycle of operation. Consequently, the movable contact arms of the reversing relays cross over, or return, to the position shown in the drawing. Such cross over of the reversing relay 16 immediately reverses the direction of current flow through the integrating relay 15 and its arm 25 now moves toward the stationary contact 27. The other reversing relay, now having closed its contacts 42, 43, completes the charging circuit through the motor field windings and the other surge capacitor 46 said circuit comprising the lead 51, contacts 43, 42 (of the reversing relay 40) lead 53, motor field windings 33, 31, lead 50, capacitor 46 and lead 48. The resulting current pulse advances the motor rotor another tooth thereby adding another unit to the counting mechanism.

It will now be clear the counting mechanism indicates the number of contact closures of the sensitive integrating relay 15. Since the movement of this relay from one stationary contact

to the other is known in terms of the quantity of light falling upon the photocell, the integrated quantity of light falling upon the photocell is obtained by noting the total counts on the counting mechanism.

The capacitors 71, 72, connected across the movable coils of the reversing relays 16, 40, respectively, serve to damp the movement of such movable coils to prevent contact bounce. The resistor 73 and capacitor 74, shown connected into the circuit by dotted lines 75, 76, introduce a small surge through the movable coil of the sensitive integrating relay to prevent sticking of the relay contacts as the direction of current flow through its movable coil is reversed. The damping capacitors 71, 72 and the contact release circuit comprising the resistor 73 and capacitor 74, are not required for functional operation of my device but serve to promote reliable operation.

It is to be understood that the invention is not limited to the particular light integrating apparatus herein shown and described as the current or voltage delivered to the movable coil of the sensitive integrating relay may be a function of some variable other than light intensity, and changes may be made in the circuits and circuit components without departing from the spirit and scope of the invention as set forth in the following claims.

I claim:

1. In apparatus for integrating an electrical quantity, the combination with an integrating instrument including a movable coil mounted for oscillation in a magnetic field and carrying a contact arm cooperating with a set of relatively fixed contacts, and a polarity reversing switch connected between the said movable coil and the

30

source of the electrical quantity to be integrated, of a source of D.-C. potential, a pair of capacitors connected in series across said D.-C. potential source, an electro-magnetic counting mechanism

5 including a coil having one side connected to the common side of the capacitors, a second reversing switch including a pair of stationary contacts individually connected to opposite sides of the D.-C. potential source and a movable contact 10 connected to the other end of the coil of the counting mechanism, said second reversing switch being controlled by the contacts of the integrating instrument.

2. The invention as recited in claim 1, wherein 15 each of the reversing switches comprises a movable coil mounted for oscillation in a magnetic field, a movable contact carried by the movable coil, and a pair of spaced stationary contacts adapted for engagement by the movable contact, the said movable coils of the two reversing switches being energized simultaneously upon closure of the contacts of the integrating instrument.

3. The invention as recited in claim 2, in combination with a resistor and capacitor connected in series between the movable coil of the integrating instrument and the movable contact of the second reversing switch.

ROSWELL W. GILBERT.
